SPINNING OR ROVING FRAME.

1,370,407.

Specification of Letters Patent.

Patented Mar. 1, 1921.

Application filed April 19, 1919. Serial No. 291,305.

To all whom it may concern:

Be it known that I, LEON W. CAMPBELL, a citizen of the United States, residing at Providence, in the county of Providence, 5 State of Rhode Island, have invented certain new and useful Improvements in Spinning or Roving Frames, of which the following is a specification.

My invention relates to spinning and roving frames, or like textile apparatus, and consists of improvements in the construction and arrangement of the drawing-rolls. The 10 object of my improvement is to provide a system of drawing-rolls which will operate on the sliver or roving to draw its fibers more nearly in proportion to their length, whereby a stronger, smoother and more uniform yarn is obtained in the finished product. To this end my improvement consists 15 essentially in providing means for acting on the sliver or roving positively at two points arranged at a distance apart, while also employing a third means for drawing the sliver through frictional contact only, the friction 20 means being interposed between the two positively acting means.

The invention is fully described in the following specification, illustrated by the accompanying drawings, in which like reference characters designate like parts. In the 25 drawings:

Figure 1 is a side elevation of a portion of a spinning-frame showing my improved system of drawing-rolls applied thereto; and 30 Fig. 2 a plan view of the same.

Referring to the drawings, 2 designates the front rail of the frame of the machine on which are mounted a series of standards or brackets 3 for supporting the drawing- 35 rolls. The brackets 3 are provided with suitable bearings 4 for receiving the journals 5 of a fluted cylinder 6 which is divided longitudinally into the several bottom-rolls 7-7. At the front of the brackets 3 are inclined shelves 8 on which are mounted the adjustable bearings 9 for the front rolls 10. The bearings 9 are constructed in the form of journal-blocks and are secured to the shelf 8 by means of bolts 11. The bolts 11 40 extend through slots 12 in the shelves 8 whereby to provide for adjusting the front rolls 10 in an inclined plane toward and away from the rear fixed rolls 7.

The brackets 3 also carry fixed bearings 45 arranged between the bearings 4 and 9 and elevated slightly thereabove. The bear-

ings 14 receive the journals 15 of a cylinder 16 which is divided into a series of friction rolls 17. In some cases the peripheries of the rolls 17 may be scored with circumferential grooves 18, see Fig. 2 for receiving the strand of the roving or sliver S whereby to increase the contact of the strand thereagainst to insure more draft of the roll thereon, it being understood that no pressure roller is employed in conjunction with the roll 14 as is the case with the other rolls 7 and 10.

To provide for the contact of the sliver or roving S against the positive drawing-rolls 7 and 10 the usual top-rolls 20 and 21 are arranged thereabove to be pressed against the strand passing under them. As shown in Fig. 2 the top-rolls 20-20 and 21-21 are arranged in pairs connected by 70 axial spindles 22, 23 on which they rotate. The spindles 22 and 23 are held in position at their centers by means of a bearing-member or arm 25 reaching forwardly from the rear of the standards 3. As shown in the 75 drawings the arm 25 is constructed from a strip of sheet-metal bent into a loop 26 at its rearward end to adapt it to be supported from a horizontal rod 27. The end of the loop 26 is bent back to form an extension 28 arranged in parallel, spaced relation with the vertical portion 29 of the arm 25, and a screw 30 inserted therethrough serves to bind the sides of the loop against the rod 27. The rod 27 is supported at its ends by arms 80 31 projecting rearwardly from the end brackets 3 of the series. As shown in Fig. 2, the ends of the rod 27 are reduced at 32 and inserted through holes in the arms 31 and nuts 33 applied thereto to hold the rod 95 in place.

The bearing for the spindle 22 of the top-rolls 20-20 is formed by suitably shaped ears 34 bent up from the sides of the arm 25. On the other hand, the bearing for the 100 spindle 23 of the front rolls 21-21 is made separate from the arm 25 in order that it may be adjusted longitudinally thereof to position the rolls 21-21 in accordance with the adjustment of the lower rolls 10. For 105 this purpose the bearing 35 is constructed with two opposite side-plates 36-36 straddling the sides of the arm 25 and formed with bent over guides or cleats 37-37 overlapping its under edges. The side-plates 110 36-36 are cut away at 39 to form bearing-seats for the roll-spindle 23 and are connect-

ed at the top by cross-strips 40, 41. Reaching down through the forward cross-strip 41 is a set-screw 42, the end of which binds against the top of the arm 25. By loosening the set-screw 42 the bearing member 35 may be slid along the arm 25 and secured in its position of adjustment by clamping the screw down against the arm. The top-rolls 20 and 21 are generally covered with leather or other cushioning material and are pressed down against the bottom-rolls 7 and 10 by means of weights suspended from a saddle, not herein shown, which rests on the roll-spindles 22 and 23 as usually arranged in machines of this type.

Extending across the back of the frame at the rear of the drawing-rolls is a horizontal, flat bar 45 which is supported at its end in slots 46 in the arms 31 of the end brackets 3. The bar 45 is provided with suitably-spaced trumpet-like openings 47 through which the strands S of sliver or roving are led to direct them to the rolls.

Projecting forwardly from the front-rail 2 of the frame is the usual thread-board 48 to which are hinged the guide-members 49 carrying wire "pigtailed" or thread-guides 50. From the guides 50 the strands S lead down to the travelers 51 on the spinning-rings 52 which spin the yarn onto the bobbins B. The construction and arrangement of my improved spinning or roving frame having now been described in detail, its method of operation will next be explained.

It is to be understood that the two sets of bottom-rolls 7 and 10 are rotated positively and continuously by means of gearing at their ends, not herein shown, but of the usual arrangement as generally provided on spinning-frames. The intermediate friction-roll 17 is also driven positively from the same train and the gearing is arranged to impart a faster rate of speed to the front-rolls 10 than to the other rolls 7 and 17. The intermediate rolls 17 may also be geared to rotate faster than the rolls 7, or the same effect can be accomplished by making the rolls 17 of greater diameter as illustrated in the drawings to provide for a greater surface speed of their peripheries.

In preparing the machine for operation the strands of sliver S are led through the trumpet-guides 47 in the rear bar 45; thence between the back rolls 7 and their top-rolls 20; next over the intermediate rolls 17; and down between the front-rolls 10 and their top-rolls 21. From the front-rolls 10 the strands S lead down through the thread-guides 50 to the ring-travelers 51 to be twisted thereby and wound onto the receiving bobbins B.

As the strands S pass between the bottom-rolls 7 and their top-rolls 20 the pressure of the latter causes them to be positively gripped and fed along at a predetermined

rate in accordance with the speed of rotation of the continuously driven bottom-rolls 7. From the rolls 7 and 20 the strands of sliver or roving pass across the top of the intermediate, friction-rolls 17 and it will be noted that through the arrangement of the latter out of line with, or raised above, the other rolls 7 and 10, the strands are caused to make a partial wrap around the peripheries of the rolls 17. That is to say, the strands S make contact with the surface of the rolls 17 throughout substantially ninety degrees of their circumference, or more if desired, in order to provide the required frictional gripping effect. As the strands S draw off from the rolls 17 and pass to the rolls 10 and 21 they are again positively gripped therebetween to feed them on to the spinning apparatus below. In the case of roving-machines the spinning-rings 52 are displaced by "fliers" in accordance with the usual arrangement. It is to be noted however that for both spinning and roving frames the arrangement of the drawing-rolls is the same and the manner in which they operate is as next explained.

The positively-driven back rolls 7 draw the strands S into the machine at a fixed rate of speed and, as before explained, the peripheral speed of the next intermediate friction-rolls 17 is slightly greater due either to their increased diameter or faster drive, or both. Now as the sliver passes over the rolls 17 the surface friction of the latter on the strands will cause a draft between the rolls 17 and 7. That is to say, the sliver will be pulled out through the drawing of its fibers one past another in the usual manner as well understood by those versed in the art.

With all systems of roll-drawing heretofore used the roving or sliver is drawn between positively engaged points along its length. That is to say, the strand is gripped positively at intervals between the several sets of top and bottom rolls which are spaced apart in fixed relation. With my present system of drawing I improve on this method by providing means for drawing the sliver through frictional contact at a point intermediate the two positive gripping means. The object of this is to allow for a draft more in proportion to the length of staple of the fibers in the sliver. With the previously used method the drawing-rolls must be set at spaced intervals and driven at relative speeds as limited by the shortest fibers of the sliver, it being understood of course that the length of fibers vary to a considerable extent in any one run of roving or sliver. Now with my improved arrangement of the drawing-rolls this variation in the length of fibers can be discounted to some extent. That is to say, the action of the intermediate friction-roll on the sliver

provides what might be termed a give-and-take draft so that the individual fibers in the strand will not be pulled out one beyond another. In other words, the draft 5 action is inductive instead of positive. This inductive action is due to the fact that the sliver or roving strand is frictionally gripped by the roll 17 throughout an extended portion of its length, while the positive 10 rolls grip it at only one point. Stated another way, the parallel fibers of the strand lie against the roll throughout the greater part of their length as they are drawn along by frictional contact therewith, but a certain 15 amount of slippage is allowed as between adjacent fibers so that there is a natural tendency to draw one in relation to the other. At the same time, all of the related fibers of any particular length or 20 section of the strand will have sufficient contact with the roll to prevent them from being drawn apart, and it is through this frictional control of the draft that a more even and uniform product is obtained.

25 After the strands leave the rolls 17 they pass between the top-rolls 21 and the bottom-rolls 10 and are positively gripped thereby to provide a still further drawing action. That is to say, the peripheral speed of the 30 driven roll 10 is greater than that of the intermediate roll 17 to effect the final draft on the sliver. With my present improved arrangement of the drawing-rolls a greater draft may be applied to the sliver or roving 35 without weakening its structure since as above explained the fibers will be more evenly and uniformly displaced in proportion to their length without the danger of drawing them apart.

40 While I have illustrated the simplest form of the invention it will be obvious that the arrangement might be extended and amplified to meet any particular requirements. For instance, instead of employing three sets 45 of drawing-rolls, the system could be extended in series, or two or more sets of friction-rolls could be used between the positive rolls. It is also to be understood that the structure and arrangement of the supporting-means for the rolls might be varied 50 and the arrangement of the rolls themselves be still further modified without departing from the spirit or scope of the invention; therefore without limiting myself to the 55 exact embodiment herein shown and described, what I claim is:

1. In a spinning- or roving-machine, the combination of pairs of coöperating top and bottom drawing-rolls adapted to act positively 60 on the strand of sliver or roving to feed it through the machine, and an auxiliary drawing-roll across which the strand leads to adapt the roll to apply an inductive draft to the fibers by its frictional contact 65 therewith, said pairs of rolls arranged with

their axes in inclined planes intersecting the plane of the axis of the auxiliary roll whereby the strand is caused to pass between the top and bottom rolls at right-angles to the plane of their axes and in a straight 70 course tangent to the periphery of the auxiliary roll.

2. In a spinning- or roving-machine, the combination of pairs of coöperating top and bottom drawing-rolls adapted to act positively 75 on the strand of sliver or roving passing between said rolls, an auxiliary friction drawing-roll arranged intermediate the pairs of top and bottom rolls and adapted to act on the strand by frictional contact to apply an inductive draft to the fibers, and means to adjust the top and bottom rolls in relation to the auxiliary roll to vary the 80 amount of the draft.

3. In a spinning- or roving-machine, the combination of continuously-driven bottom drawing-rolls, top-rolls coöperating with the bottom-rolls to positively grip the strand of sliver or roving passing therebetween to feed it through the machine, and an auxiliary continuously-driven friction-roll arranged intermediate the pairs of top and bottom rolls to adapt the strand to draw across its periphery whereby an inductive draft is applied to the fibers, said rolls arranged in such relation as to adapt the strand to draw between the top and bottom rolls at substantially right angles to the plane of their axes while leading to and from the auxiliary roll in a straight course 90 tangent to its periphery.

4. In a spinning- or roving-machine, the combination of continuously-driven bottom drawing-rolls, top-rolls coöperating with the bottom-rolls to positively grip the strand of 105 sliver or roving passing therebetween to feed it through the machine, an auxiliary continuously-driven friction-roll arranged with its periphery adapted to contact with the strand to apply frictional draft on the fibers thereof, and means to adjust one pair of top and bottom rolls in a direction inclined to the plane of the axes of the other set of top and bottom rolls.

5. In a spinning- or roving-machine, the combination of spaced pairs of coöperating top and bottom drawing-rolls adapted to act positively 115 on the strand of sliver or roving to feed it through the machine, an auxiliary friction-roll positioned intermediate the pairs of top and bottom rolls and adapted to feed the strand by frictional contact therewith to apply an inductive draft on its fibers, said pairs of top and bottom rolls arranged with their axes in inclined planes intersecting at a point beneath the axis of the intermediate roll, and means to adjust the pairs of top and bottom drawing-rolls in a direction at right angles to the plane of 120 their axes.

6. In a spinning- or roving-machine, the combination of pairs of coöperating top and bottom drawing-rolls between which the strand of sliver or roving feeds, and an auxiliary friction-roll across which the strand leads to adapt it to be fed by frictional contact to apply an inductive draft on its fibers, said auxiliary roll provided with an annular groove on its periphery for receiving the strand whereby to increase the frictional contact of the roll with the fibers.

7. In a spinning- or roving-machine, the combination with brackets carrying bearings, of bottom-rolls journaled in the bearings on said brackets, a member hinged at one end to the bracket and carrying bearings for the top-rolls, top-rolls journaled in said bearings to adapt them to rest upon the bottom-rolls, and an intermediate friction-roll journaled in bearings in the brackets and arranged between the pairs of top and bottom rolls to adapt the strand of sliver or

roving to pass thereacross as it draws between said top and bottom rolls.

8. In a spinning- or roving-machine, the combination of vertical brackets having fixed bearings, back rolls journaled in said fixed bearings, separate bearings adjustably mounted on the brackets, front rolls journaled in said adjustable bearings, a member hinged at one end to the brackets and extending across the top of the bearings thereof, a top roll journaled in bearings on said member to adapt it to contact with the back roll, an adjustable bearing at the forward end of said member, a top roll journaled in said bearing to adapt it to contact with the front roll, and an auxiliary friction-roll arranged in bearings on the brackets intermediate of the front and back rolls.

In testimony whereof I affix my signature.

LEON W. CAMPBELL.
